OVERHEAD OPENING GARAGE DOOR

Sern Madsen, Clinton, Iowa, assignor, by mesne assignments, to George L. Curtis, Eugene J. Curtis, and Charles A. Armstrong, trustees, all of Clinton, Iowa

Application July 21, 1930, Serial No. 469,434

3 Claims. (Cl. 20—19)

An object of my invention is to provide a door for garages or the like and supporting means therefor whereby the door may be raised from a closed vertical position to an open horizontal position without the necessity of having to form the door in sections and hinge the sections together.

Another object is to provide hardware for such a door of simple, durable and inexpensive construction.

A further object is to provide means for supporting a door so that it can be moved from closed to open position without providing any horizontal joints which prevent good architectural design and make an ugly instead of a beautiful door.

Still another object is to provide an overhead opening door which does not require a prohibitive amount of head room and consequent high ceiling.

Another object is to provide a door and hardware therefor, the hardware being entirely supported from the side jambs of the door without the necessity of overhead supports, which add to installation expense.

Still a further object is to provide an arrangement for supporting a garage door so that in opening the door, the lower part is pushed outwardly and thus away from a car in the garage so as to eliminate the necessity of providing any space within the garage close to the floor for operation of the door from one position to another.

Another object is to support the door in open position under the ceiling of the garage and thus out of the weather.

Still another object is to provide counter-balancing springs for the door, thus obviating the necessity of providing weights, the springs being vertically mounted close to the door jambs so there is a minimum of danger in case of breakage or other accidents which might release the spring.

A further object is to provide door hardware which is readily adaptable to various types of doors and wall structures.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Figure 1 is an inside elevation of a door and hardware therefor embodying my invention, the door being shown in closed position,

Figure 2 is a top plan view of the same.

Figure 3 is an enlarged sectional view taken on the line 3—3 of Figure 1 showing the door closed.

Figure 4 is a similar sectional view on a reduced scale showing the door opened.

Figure 5 is an enlarged sectional view on the line 5—5 of Figure 1.

Figure 6 is an enlarged sectional view on the line 6—6 of Figure 4.

Figure 7 is an enlarged sectional view on the line 7—7 of Figure 1.

Figure 8 is an enlarged sectional view on the line 8—8 of Figure 1 and

Figure 9 is a sectional view on the line 9—9 of Figure 7 showing a side elevation of a portion 15 of the supporting hardware for the door.

On the accompanying drawings, I have used the reference numerals 10 to indicate the side jambs of a door opening in a wall of a garage or the like. The head jamb of the door opening 20 is indicated at 14. The door itself is indicated by the reference numeral 16 and is built in one solid unit without any joints from top to bottom or from side to side as in most types of overhead opening doors.

The supporting hardware for the door 16 includes supporting angles 18, the projecting flanges of which are to the sides of the angles farthest from the door opening. The supporting angles 18 are adapted to be secured to the side jambs 10 30 by lag screws or the like 20 extending through slots 21 in the angles. A slot 21 is provided for each lag screw 20.

Two of the supporting angles 18 are provided, one on each side jamb 10. Since they and all 35 parts fastened to them are identical, I will describe but one of them. Secured to the supporting angle 18 by means of bolts 22 is a bracket casting 24. The bracket 24 has an upwardly and inwardly inclined arm 26 as best shown in Figure 9 to which is connected an arched or curved roller supporting bar 28, preferably of angle construction. Bolts 30 are utilized for securing the roller support 28 to the arm 26 of the bracket 24.

The inner end of the roller support 28 is supported by a tie rod 32 connected with the roller support 28 at one end and with the upper end of the supporting angle 18 at its other end.

A bracket 34 (see Figure 2) is provided on the roller support 28 for the tie rod to extend through. 50 The inner ends of the roller supports 28 are connected together by an angle bar 36 and suitable braces 38 which prevent undesired transverse movement of the inner ends of the arms 28.

Secured to the lower end of the angle 18 is a 55

5 pivot arm 40 braced by means of a bar 42. The pivot arm 40 and the bar 42 support a pivot bolt 44 on which is pivotally mounted a door arm 46. The lower end of each door arm 46 is connected with an arm 48 of an aligning shaft 50.

10 The aligning shaft 50 is pivotally connected with the lower part of the door 16 by means of bearing straps 52 and bearing blocks 54. Set collars 56 prevent longitudinal movement of the aligning shaft 50 with respect to the bearing straps 52.

15 Connected as by bolts 57 selectively cooperable with openings 59 to the upper end of the supporting angle 18 is a spring arm 58. A vertically arranged coil spring 60 has its upper end connected with the spring arm 58 and its lower end hooked over a spool-like fitting 62 secured to the door arm 46 by means of a bolt 64 best shown in Figure 8. A plurality of openings 66 are provided in the door arm 46 so that the bolt 64 can be placed in any one of them for adjusting the tension of the spring 60, as desired.

20 25 30 A plurality of spaced rollers 68 are rotatably mounted on bolts 69 and sleeves 71 which are connected with the roller supports 28 as best shown in Figure 6. The door 16 is provided with channel or angle iron tracks 70 which are secured to the inner surface of the door 16 by means of screws 72, as best shown in Figure 7 for coaction with the rollers 68.

Practical operation

35 The door 16 when closed stands in the vertical position shown in Figure 3 of the drawings with its inner surface in the same plane as the inner surfaces of the door jambs. Above the lowermost roller 68 a flat bar stop 74 (see Figure 7) is secured to the door 16 by screws 76 and engages the jamb 10. Below this roller a flat bar stop 78 is secured to the jamb 10 and engages the door 16 when in closed position. These stops insure correct alignment of the door with the door jamb and prevent the infiltration of air.

40 45 50 When the operator is on the inside of the garage, he pushes outwardly on the lower part of the door 16, after releasing the lock bar 80 (see Figure 1) by turning the lock handle 82. If he is on the outside of the garage, he pulls the lower part of the door outwardly. A handle can be provided on the lower part of the door for convenience in opening the same.

55 60 65 The door is immediately guided by the two door arms 46 and kept in exact parallelism by the aligning shaft 50 so that it will travel substantially in an arc of a circle outward and upward. The points on the guide tracks 72 which bear against the lowermost rollers 68 tend to fulcrum about the rollers as a center. Thus movement of the lower part of the door outwardly causes inward movement of the upper end of the door.

70 75 To insure that the upper end will be properly guided inwardly, I provide resilient guide fingers 84 secured to the brackets 24 by means of bolts 86 and held against pivoting on the bolts by lugs 88. Guide lugs 90 are mounted on the door 16 and extend behind the guide fingers 84 as best shown in Figure 7. In Figure 3, it will be noted that the upper end of the guide finger 84 is inwardly curved so that the lug 90 sliding behind it will force the upper end of the door 16 to swing inwardly.

In addition to the rotating movement of the door about the lowermost rollers 68 as a fulcrum, the door will also roll upwardly on these rollers

until the tracks 70 engage the next pair of rollers, as shown in dotted lines in Figure 4. Further opening movement of the door will cause the tracks 70 to successively engage the other pairs of rollers until in the open position shown in full lines in Figure 4 the door is supported by the uppermost rollers and the door arms 46.

5

10 The door in the open position is substantially horizontal and is substantially balanced on the uppermost rollers and consequently there is no tendency for its return to closed position.

15 In the closing of the door, a strap-like handle 92 hanging down from the aligning shaft 50 may be grasped by the operator and pulled downwardly which will reverse the operation of the door with the two springs 60 at all times exerting an upward balancing force so that the door operates easily. In the full open position, the springs prevent the door from starting down of its own accord since the door is substantially 20 counterbalanced by the coaction of tracks and rollers (see Figure 4) and but slight spring pressure is required to retain it in such position. Once started down, however, it moves slowly and will come to rest in a partly opened position (as 25 shown in dotted lines), such position being determined by the adjustment of the springs 60. Beyond this neutral or balanced position the weight of the door, acting through the lever like arms 46, overcomes the tension of the springs 30 60, which closes the door and holds it shut.

It will be noted that when the door is in a closed vertical position, the tension of the springs is greatest because they are stretched most but because of the angle of the arms 46 relative to 35 the springs (see Figure 3) the door may be easily started from closed position. In the opening movement of the door, the springs are contracted and the door shifts from vertical to inclined and then to horizontal position, which gradually 40 decreases its effective weight on the door arms 46 and consequently the springs 60.

45 This feature is advantageous as at all positions of the door, it causes an approximate balance between the springs and the door.

It will be noted that the parts are so arranged that it is necessary to attach only the supporting angles 18 to the garage and the bearing straps 52 to the garage door. This simplifies installation expense and eliminates the necessity for having overhead supports. The springs 60 are arranged vertically close to the door opening instead of extended horizontally overhead as in most types of door hardware. This reduces the danger of breaking springs to a minimum as a broken spring overhead will fall downwardly and may thereby cause an accident.

I have provided a means for adjusting the door 16 vertically relative to the door frame and such means is best disclosed in Figure 9 of the drawings. On each of the bracket castings 24 which are secured to the angles 18, a U-shaped ear 98 is provided. On the lag screws 20 above each ear 98 angle-shaped brackets 94 are provided. A bolt 96 extends through the bracket 65 94 and the U-shaped ear 98 and is provided below the ear with a nut 100. Thus it will be seen that loosening of the lag screws 20 (four in each angle 18) and then tightening of the nut 100 will raise the entire supporting angle 18, and 70 the door hardware carried thereby, the slots 21 through which the lag screws 20 extend permitting of such vertical adjusting movement of the angles 18 while loosening of the nut will allow lowering of the angle and its hardware. There- 75

after the lag screws 20 can be retightened to positively retain the angle in the position to which it has been adjusted. Since the members 40 and 42 are carried by the angle 18 and the 5 pivots 44 are carried by the members 40 and 42, the entire door 16, which is connected by the arms 46 with the pivots 44, is thus vertically adjustable.

After such adjustment is made, the lag screws 10 may be tightened for retaining the angles in their adjusted position. This construction allows individual adjustment of each angle 18 so as to align the lower edge of the door 16 with the floor, and the lower edge may be positioned 15 just as close to the floor as desired.

It will be noted that the pivot bolts 44 are located a substantial distance inward from the door jambs. This provides room to attach the counterbalancing spring to the arm and also 20 produces a quicker upward movement of the lower end of the door. It is a decided advantage to have the door moved with an upward component movement after it starts to open outwardly inasmuch as it thus clears the sill at 25 the bottom of the door and also clears drifted snow for instance much more quickly than when the arm 46 is pivoted close to the door jamb. Referring to Figure 3 it will be particularly noted that in the closed position of the door, the arm 30 is at an angle instead of being practically vertical as when the pivot bolt 44 is located close to the jamb. The bars 40 and 42 space the pivot 44 inwardly to accomplish this result.

Some changes may be made in the construction and arrangement of the parts of my device without departing from the real spirit and purpose of my invention, and it is my intention to cover by my claims, any modified forms of structure or use of mechanical equivalents, which may 40 be reasonably included within their scope.

I claim as my invention:

1. In a structure of the character disclosed, a door frame including side jambs, a door associated therewith, door hardware for supporting said door so that it can be raised from closed 45 vertical to open horizontal position including a pair of vertical supporting members carrying said door hardware and being provided with vertical slots and fastening means through said 50 slots and into said side jambs and vertical bolt connections between said side jambs and said

supporting members whereby said supporting members may be individually adjusted relative to the side jambs to which they are secured for thereby adjusting the door relative to said door frame.

2. In a structure of the kind described, a door frame, a door adapted to be in vertical position adjacent the door frame when closed and to be in horizontal raised position when opened, track and roller means for supporting and guiding the upper part of the door during its movement to and from its respective positions, a pair of arms for guiding the lower part of the door during such movement, each of said arms being pivoted at one end to the door near its lower 15 part and being fulcrumed to the door frame and intermediate the top and bottom thereof, springs, each having one end secured near the upper end of the door frame and the other end secured to one of said arms intermediate its 20 ends and constantly under tension in all positions of the door, said fulcrum points being so spaced inwardly from the door frame that the initial opening movement of the bottom of the door is in an upwardly inclined arc and so that 25 in the movement of the door from closed to full open position the arms travel through an arc substantially less than 180°, whereby the springs always act substantially removed from dead centers at all points of travel and whereby the door 30 is always balanced by the springs, thus eliminating slamm'ng at both top and bottom.

3. In a structure of the kind described, a door frame, a door adapted to be in vertical position adjacent the door frame when closed and to 35 be in horizontal raised position when opened, track and roller means for supporting and guiding the upper part of the door during its movement to and from its respective positions, a pair of arms for guiding the lower part of the door 40 during such movement, each of said arms being pivoted only at one end to the door near its lower part and being fulcrumed only at its other end at a point spaced substantially inwardly from the door frame and intermediate the top and 45 bottom thereof and springs, each being under constant tension in all positions of the door having one end secured near the upper end of the door frame and the other end secured to one of said arms intermediate its ends.

SERN MADSEN.
